UNITED STATES PATENT OFFICE.

WILLIS H. WEISSBROD, OF GREENFIELD, MASSACHUSETTS.

KEY CASE.

Application filed December 1, 1925. Serial No. 72,467.

To all whom it may concern:

Be it known that I, WILLIS H. WEISSBROD, a citizen of the United States of America, and a resident of Greenfield, in the county 5 of Franklin, and State of Massachusetts, have invented a new and useful Key Case, of which the following is a specification.

My invention relates to improvements in pocket cases especially designed for holding 10 and carrying keys, and consists essentially of an intermediate, flexible body part having overlapping, flexible flaps provided with special fastening means, and a backing attached to said body part to stiffen the same 15 and afford supporting means for a key-carrying chain, together with such other parts and members as may be necessary or desirable in order to render the case complete and serviceable in every respect, all as here- 20 inafter set forth.

The primary object of my invention is to produce a case, of the character described, which is comparatively simple and inexpensive to manufacture, yet durable, convenient, 25 neat, and attractive in appearance, well adapted to prevent the keys contained in said case from wearing the pocket in which the same is carried, and capable of containing a larger bunch or larger number of keys 30 than most other key cases of the same size.

A further object is to provide such key case, with fastening means for the flaps, whereby the latter when folded are securely held in proper relation to each other and to 35 the body of the case, thus not only enhancing the appearance of the case, but reducing to the minimum the wear incident to rubbing parts, and rendering said case more convenient to handle.

Other objects and advantages will appear 40 in the course of the following description.

I attain the objects and secure the advantages of my invention by the means illustrated in the accompanying drawings, in 45 which—

Figure 1 is a front elevation of a key case which embodies a practical form of my invention, showing the same closed; Fig. 2, 50 an isometric view of said case when open and, Fig. 3, an enlarged vertical section through the closed case, taken on lines 3—3, looking in the direction of the associated arrow, in Fig. 1, an intermediate portion of the case being broken out.

Similar reference characters designate 55 similar parts throughout the several views.

Referring to the drawings, it will be seen that my key case comprises a folder of flexible material consisting of a back or body 1 having articulated to the left- and right-hand, longitudinal edges thereof, respectively, a wide flap 2 and a narrow flap or cover 4, a backing strip or piece 5 stitched to the inside of said body, and having its top portion turned over to form a deep or wide hem or roll 6 through which extends from end to end a passageway 7, a flexible, key-supporting member, preferably consisting of a chain 8 passing through said passageway and provided with a clasp 9 to and from which the ends of said chain may be attached and detached, male fasteners 10—10, one of which is secured to said backing in front in the center of said roll, and the other of which is attached to said first-named flap 70 near the bottom in the longitudinal center thereof, and female fastening members 11—11, both of which are secured to said cover adjacent to the top and bottom edges and inset a short distance from the free longitudinal edge thereof.

The edges of the body 1, flap 2, and cover 4 are turned over on the inside and stitched (as at 17) to form a hem 12, in the customary manner. The lower edge of the 85 backing 5 is inserted between the back 1 and the hem 12 at the bottom, and the stitching 17 for such hem and which passes through the body 1 and the hem-forming part also passes through said backing. The 90 stitching for the hem 12 at the top of the body 1 also passes through the rear portion of the roll 6. Additional transverse lines of stitching 13 and 14 are provided, also longitudinal lines of stitching 15—15, for 95 the purpose of securing the backing 5 to the body 1 intermediate of the ends thereof. The stitches at 13 pass through the body 1 and the backing 5, including the part of 100 said backing that forms the back of the roll 6, and the lower end portion of which is inserted between said body and the main part of said backing. The stitches at 14 and 15 pass through the body 1 and backing 5, the vertical or longitudinal stitches 105 being adjacent to the longitudinal edges of said backing. The backing 5, being thus securely attached to the body 1, supplies the additional stiffness or stability needed by said body, even though said backing be made of flexible material similar to that of which 110 said body is made, affords a suitable bed

for the keys suspended from the chain 8, and with it the double thickness at the back is provided, the flap 2 and cover 4 provide a double thickness at the front, 5 when said flap and cover are closed.

The chain 8, shown in connection herewith, is of the ball and link type, and the clasp 9 is so constructed that the balls at the ends of said chain can be snapped into 10 and out of engagement with said clasp at the center thereof. This chain and clasp are old and well known. Whenever it is desired to attach a key to the chain 8, or 15 detach the same therefrom, it is simply necessary to disengage either end of said chain from the clasp 9, and, after the key has been attached or removed, reengage such end with said clasp.

In the upper part of the flap 2, directly 20 over the male fastening member 12 which is attached to said flap, is an opening 16. The opening 16 is in position to receive therein the male fastening member 10 at the top of the backing 5, when said flap is closed. 25 The female fastening members 11 are in position to engage with the male fastening members 10, when the flap 2 and cover 4 are folded, with the latter outside of the former, over and onto the body and backing.

To close the key case properly, after the desired number of keys has been placed on the chain 8, or after a key has been used or removed, the flap 2 is first folded over 30 onto the chain 8 and keys connected therewith and supported on the backing 5, with the male fastening member 10, at the top of the backing on the front of the roll 6, in the opening 16 in said flap, and then 35 the cover 4 is folded over onto said flap, and the female fastening members 11 are snapped into engagement with said male fastening member and the male fastening member 10 at the bottom of the flap. The folded 40 parts are thus securely attached together and held in proper superimposed relationship so that there is no sagging of the flap and cover or distortion generally of the case as a whole, on the contrary, said case maintains 45 its symmetrical form and outline and neat and uniform appearance during such times as it is closed.

To open the case, simply disengage the 50 female fastening members 11 from the male fastening members 10 and open first the cover 4 and next the flap 2. Access is now had to the keys on the chain 8, and said keys can be used conveniently, and readily 55 attached to and detached from said chain, as previously observed.

The chain 8 permits the keys to lie quite flat, unless there be a great number on said chain. But whether there be few or many 60 keys on the chain, they can be arranged in the case without undue bunching, and

said case can be folded to enclose said keys and form a very compact package.

More or less change in the shape, size, construction, and arrangement of some or all of the parts of this key case may be 70 made, without departing from the spirit of my invention or exceeding the scope of what is claimed.

What I claim as my invention, and desire 75 to secure by Letters Patent, is—

1. As an improved article of manufacture, a key case comprising a flexible body having articulated flaps, a flexible backing of substantially the same width as said body, and turned over at the top to form a passageway which extends across said body with front and back sides which are continuous and unbroken, means to fasten said backing to said body, which means passes through the turned-over part of the backing near the bottom edge thereof, a key-supporting element extending through said passageway, out through the ends thereof, and across the backing in front above the bottom edge of the same, and fastening means for said flaps. 85

2. As an improved article of manufacture, a key case comprising a body having an articulated flap and an articulated cover, a backing attached to said body, a chain supported by said backing, said chain being provided with means to connect and disconnect the ends thereof, a fastening member attached to the upper part of said backing in front, said flap having an opening therein to receive said fastening member when said flap is closed, a fastening member attached to said cover to engage and disengage said first-named fastening member when said flap and cover are closed, a fastening member attached to said flap below said opening therein, and another fastening member attached to said cover to engage and disengage said fastening member on said flap when said flap and cover are closed. 90

3. As an improved article of manufacture, 100 a key case comprising a body having an articulated flap and an articulated cover, a backing attached to said body, and provided with key-supporting means, a fastening member attached to the upper part of said

backing in front, said flap having an opening therein to receive said fastening member when said flap is closed, a fastening member attached to said cover to engage and disengage said first-named fastening member when said flap and cover are closed, a fastening member attached to said flap below said opening therein, and another fastening member attached to said cover to engage and disengage said fastening member on said flap when said flap and cover are closed. 110

4. As an improved article of manufacture, 115 a key case comprising a body having an articulated flap and an articulated cover, said flap being perforated at the top and pro-

vided at the bottom with a male fastening member, and said cover being provided at the top and bottom with female fastening members, a backing secured to said body and formed with a lateral passageway there-through at the top, and provided with a male fastening member in position to enter the perforation in said flap and the upper female fastening member on said cover when

5 said flap and cover are closed, the lower fe-

male fastening member on said cover and the male fastening member on said flap being then capable of engagement with each other, and a chain extending through said passageway and across said backing in front, 15 said chain being provided with means for the engagement and disengagement of the ends thereof.

WILLIS H. WEISSBROD.
